UNITED STATES PATENT OFFICE.

ISAAC M. RHODES, OF HANCOCK, MICHIGAN.

APPARATUS FOR CUTTING CIRCULAR WOODEN PLATES.

SPECIFICATION forming part of Letters Patent No. 352,003, dated November 2, 1886.

Application filed May 28, 1886. Serial No. 903,560. (No model.)

To all whom it may concern:

Be it known that I, ISAAC M. RHODES, of 5
Hancock, in the county of Houghton and
State of Michigan, have invented a new and
useful Improvement in Apparatus for Cutting
Circular Wooden Plates, of which the follow-
ing is a specification.

My invention consists in the improved con-
struction of an apparatus for cutting wooden
10 wheels, circular plates, disks, and annular
grooves, and which possesses advantages in the
points of simplicity and cheapness of construc-
tion and rapidity and accuracy in operation,
all as will be hereinafter fully described, and
15 pointed out in the claim.

Referring to the accompanying drawings, Fig-
ure 1 is a perspective view of my improved
apparatus. Fig. 2 is a longitudinal vertical
20 sectional view of the same adjusted in oper-
ative position, and Fig. 3 is a detail view of
one of the adjustable cutters.

The same letters of reference indicate corre-
sponding parts in all the figures.

Referring to the several parts by letter, A
25 represents the base-plate, which is formed with
the vertical upwardly-extending exteriorly-
threaded hub B, which forms a central bear-
ing for the operating-handle E, which carries
the adjustable cutters. The base-plate A is
30 formed with a central aperture, C, through
which is inserted a wood-screw, D, which
screws down into the wood and secures the
base-plate thereto, this screw being short or
long, according to the thickness of the wood
35 being operated upon.

E represents the operating-handle, which is
usually made about twenty-four inches in
length, and a handle of this length will, with
the adjustable cutters, cut wheels of from four
40 to twenty inches in diameter, as may be de-
sired. The central portion of this handle,
which is enlarged, is formed with a vertical
screw-threaded aperture, F, which adapts the
handle to fit and turn upon the threaded hub
45 B of the base-plate A. Each end of the han-
dle, to each side of the central aperture F, is
formed with a vertical longitudinal slot, G G,
and in each slot fits the shank H of one of the
cutters I. These cutters are formed with the
50 body portion J, formed at its upper end with
the shoulder K, which fits against the lower
side of the slotted handle, and the shank H,

which extends up through the slot and has
screwed on its threaded upper end a nut, L,
which serves to hold the cutter in its adjusted 55
position, a washer, M, being placed between
the said nut and the upper surface of the slot-
ted handle. The lower end of each cutter is
formed with the pointed toe N, having the in-
clined forward face and the bifurcated heel O, 60
which forms the sharp cutting-blades O' O',
the cutters being arranged in the handle, as
shown, so that as the handle is revolved the
cutting-heel of each cutter cuts into the wood
and the pointed inclined toe of the other cut- 65
ter operates to remove or take out the strip so
cut, as will be readily understood; or, if one
cutter alone is used instead of two, its toe, on
its next revolution, will remove the strip cut
by its heel. I prefer, however, to use two 70
cutters, as they divide the labor, making the
strip cut by each cutter only one-half as thick
as it would be if only one cutter were em-
ployed; and, further, by using two cutters the
annular groove is carried down straighter, or 75
with a flatter bottom than if only one cutter
were used, and the apparatus works steadily
and is prevented from tilting to one side while
in operation.

The front edge of each end of the handle is 80
provided with the two scales P P, extending
practically from the center of the handle to
the outer end of each slot G, these scales be-
ing graduated into inches and fractions there-
of, and the scales are secured, as shown, to the 85
front edges of each end of the handle, so that
their marks or gradations extend down into
close proximity to the forward edge of the
shoulder of each cutter, the said shoulder ex-
tending directly over the center of the heel 90
and toe of each cutter, and it will be seen
that by this arrangement the cutters can be
instantly adjusted to the precise point de-
sired. Each half-inch of real length on each
scale is preferably marked as a full inch, the 95
object of this arrangement being that when
the operator wishes to cut a circle of, say,
twelve and three-fourths inches in diameter
he can rapidly adjust each cutter to the num-
ber 12 $\frac{3}{4}$ of each scale, without stopping for 100
any calculations, and will then cut a circle of
twelve and three-fourths inches in diameter,
each cutter being six and three-eighths inches
from the center of the handle. The bifurcated

cutting-heel O of each cutter extends down below the level of the inclined point or toe thereof, so that as the toe is removing the strip cut by the other cutter or by its own heel, 5 when only one cutter is employed, the bifurcated heel is cutting a deeper strip, over which its toe passes in advance.

The operation of my improved apparatus is as follows: The cutters having been adjusted 10 to the right points and the base-piece A secured to the wood by means of a wood-screw of suitable length, the handle is rotated by the operator, the cutters operating as described, and as the handle is rotated it works down 15 upon the screw-threaded hub of the base-piece, so that the cutters cut on a spiral, lower and lower, until they cut entirely through the wood, and thus complete the wheel or disk, the rapidity with which the cutters cut the groove 20 being regulated by the number of threads to the inch on the hub of the base-piece; or, if desired, the groove may be cut to the requisite depth and so left. It will be seen that this apparatus may also be used for cutting 25 holes of any required diameter.

From the foregoing description, taken in connection with the accompanying drawings, the construction, operation, and advantages of my improved apparatus will be readily understood. It will be seen that it is simple and 30 cheap in construction, while at the same time it is very rapid, accurate, and efficient in its operation, and can be readily operated by hand by any person to cut wooden wheels, circular-plate disks, annular grooves, and 35 holes.

I am aware that a tool for cutting holes has been formed of a bar carrying the adjustable

cutters, handles, and an intermediate sliding screw or bolt which is in operation to be 40 screwed into a previously-bored hole in the material to be operated upon and then rotated. An imperforate disk cannot be cut out by this tool, as the bolt must travel entirely through the material. I am also aware that a tool for 45 beveling the edges of barrel-heads has been formed of a slotted bar having handles at its opposite ends, one of which has a penetrating device on which the bar revolves but does not move vertically. The cutter is mounted in a 50 holder adjustable in the slot of the bar; and I do not claim such as of my invention.

I am also aware that a machine for cutting circles has been formed of a base having a 55 wood-screw on its under face and a screw-threaded post projecting vertically from its top. A threaded sleeve worked on this post, and a longitudinally-adjustable cutter-bar was secured to this sleeve by a removable block having loops and a set-screw; and I do not 60 claim the same as of my invention.

Having thus described my invention, what I claim, and desire to secure by Letters Patent, is—

The combination, with the hollow stationary 65 externally-threaded hub having a base formed with an aperture in alignment with the longitudinal central axis of the hub, and a removable wood-screw passed through said aperture, of a rotary cutter-bar having a screw-threaded aperture through which the hub 70 passes, substantially as set forth.

ISAAC M. RHODES.
